United States Patent Office

Des. 218,305
Patented Aug. 11, 1970

218,305

VALVE BODY

Aaron Kutz, Forest Hills, N.Y., assignor to Fluidic Controls Corporation, South Hackensack, N.J., a corporation of New Jersey

Filed Dec. 3, 1968, Ser. No. 14,767

Term of patent 14 years

Int. Cl. D23—01

U.S. Cl. D23—19

FIG. 1

FIG. 2

FIG. 3

FIG. 4

FIG. 5

FIG. 1 is a top plan view of a valve body showing my new design;

FIG. 2 is an elevational view taken from the right end thereof;

FIG. 3 is a side elevational view thereof;

FIG. 4 is an elevational view taken from the left end thereof; and

FIG. 5 is a bottom plan view thereof.

I claim:

The ornamental design for a valve body, as shown.
